UNITED STATES PATENT OFFICE.

JOHN R. HOLLOWAY, OF WESTVILLE, NEW JERSEY, AND HENRY S. JACOBS, OF PHILADELPHIA, PENNSYLVANIA; SAID HOLLOWAY ASSIGNOR TO SAID JACOBS.

BAIT OR OTHER NET.

SPECIFICATION forming part of Letters Patent No. 655,976, dated August 14, 1900.

Application filed June 16, 1900. Serial No. 20,490. (No model.)

To all whom it may concern:

Be it known that we, JOHN R. HOLLOWAY, of Westville, county of Gloucester, State of New Jersey, and HENRY S. JACOBS, of the city 5 and county of Philadelphia, State of Pennsylvania, have invented an Improvement in Bait or other Nets, of which the following is a specification.

Our invention has reference to supporting-
10 frames for bait or other nets; and it consists of certain improvements fully set out in the following specification and shown in the accompanying drawings, which form a part thereof.
15 The object of our invention is to provide a suitable construction of net-support which shall give a large area of suspension in use, but which may be readily dismantled and packed in a small space for transportation
20 purposes.

In carrying out our invention we provide a suitable central clamp of special construction adapted to clamp the adjacent ends of four radiating rods, the outer ends of the rods being 25 provided with means wherewith to attach the four corners of the net. The net may have its corners provided with rings or fasteners, whereby it can be quickly attached or detached, with suitable hooks or fasteners
30 on the ends of the rods. The central clamp comprises two detachable holder-pieces furnished with sockets, in each of which pieces two of the rods may be placed and oppositely directed, said socket-pieces being adapted to
35 be interlocked at right angles and held together by means of a clamping-plate fitting over the upper and inner edges of the four rods and held in place by a suitable clamping-screw having an eye or looped part which
40 may also act as a means of support for the frame as a whole.

Our improvements will be better understood by reference to the drawings, in which—

Figure 1 is a perspective view of our improved net and support ready for use. Fig. 45 2 is a longitudinal sectional elevation through the central portion thereof, taken on line 2 2 of Fig. 3. Fig. 3 is a plan view of the central clamp. Fig. 4 is a perspective view of 50 the socket-pieces and clamping part sepa-

rated, and Fig. 5 is an elevation showing our supporting-frame sustaining a mosquito-net.

A is the clamp proper and carries the four radiating rods B, the outer ends of which may be provided with snap-hooks b.

C is the net and has its four corners provided with rings D, adapted to interloop with the hooks b on the ends of the rods.

The clamp A consists of the parts E, H, and J, which are clamped together by a screw K. 60 The part E has its ends provided with tubular sockets e and the upper surface preferably grooved, as at F, to receive the inner ends of the oppositely-directed rods B. The central portion of this part E is recessed at 65 G, forming a longitudinal transverse opening below the level of the rods B. The part H is similar to the part E, with the exception that the recessed portion is on the under side, as at G'. It is provided on its ends with tubular sockets h for receiving the remaining two 70 rods B and has its upper surface grooved, as at F'. The central recessed portion G' is adapted to fit down into the recessed portion G of the part E, as clearly shown in 75 Fig. 2, and interlock. When in this position, it is held exactly at right angles to the length of the part E and also holds its rods B in the same horizontal plane with the rods B of the part E. The third part of the clamp is shown 80 at J in the form of a plate and is provided with lateral arms or projecting portions M, which may be grooved on the under portions and adapted to clamp down upon the inner and adjacent ends of the four rods B. The 85 three parts J, H, and E are held together by the clamping-screw K, which is screwed into the lower part E and draws the three parts together, so as to clamp the rods B firmly in 90 position. The upper end of this screw K is formed into a loop, so as to be adapted to act as the direct means of support for the net. The screw-threaded part is made sufficiently long to retain its connection with the lower part E and yet permit the upper parts to be 95 loosened and turned. The lower end of the screw may be upset or spread to prevent complete detachment.

In dismantling the structure the net proper is disconnected from the rods B, the screw K 100

is loosened, and the rods B withdrawn from their sockets. The screw is further loosened, so that the part H may be raised out of the socket G and turned parallel to the part E, 5 so that the clamp may be condensed into the smallest possible space.

While this invention is especially well adapted to a fish-net, it is nevertheless clear that the net may be made in the form of a 10 canopy or mosquito-net, as shown in Fig. 5, for use either for sporting purposes or in homes. We consequently do not confine ourselves to any specific construction of net proper.

While we prefer the construction here 15 shown, we do not limit ourselves to the minor details thereof, as they may be modified without departing from the spirit of the invention.

Having now described our invention, what 20 we claim as new, and desire to secure by Letters Patent, is—

1. In a net structure, the combination of 25 four radiating rods, a net having detachable means of attachment with the ends of the rods, and a detachable clamp for holding the adjacent inner ends of the rods.

2. In a net structure, the combination of 30 four radiating rods, a net having detachable means of attachment with the ends of the rods, and a detachable clamp for holding the adjacent inner ends of the rods, consisting of 35 two socket-pieces in which the inner ends of the rods are held, a clamping-plate adapted to press upon and grip the ends of the rods, and a clamping-screw for drawing the clamping-plate toward the socket-pieces.

3. In a net structure, the combination of 40 four radiating rods, a net having means of attachment with the ends of the rods, and a detachable clamp for holding the adjacent inner ends of the rods, consisting of two crossing 45 detachable pieces interlocked one with the other and both provided with radiating

sockets for the rods, a clamping-plate extending partly over each of the crossing pieces, and a clamping-screw for drawing the clamp- 45 ing-plate and crossing pieces together.

4. A net-frame consisting of two socket- 50 pieces each having oppositely-directed sockets fitted with rods for holding the net, one of the socket-pieces being fitted into a recess or depression in the other to hold it at right angles and bring the rods in the same plane, a clamping-plate fitting partly over each of the socket-pieces so as to press upon all four rods, and a clamping-screw for holding the 55 clamping-plate and socket-pieces together.

5. A clamp for uniting the radiating rods 60 of a net-support, consisting of two pieces for holding the rods in pairs adapted to interlock with each other so as to be held at right angles, combined with a clamping-plate extending partly over each of the rod-holding pieces, and a clamping-screw for drawing the clamping-plate down upon the rod-holding pieces.

6. A clamp for uniting the radiating rods 65 of a net-support consisting of the socket-piece E having sockets e on its ends and recessed portion G, combined with the crossing socket-piece H having the sockets h on its ends and the central part inverted recessed 70 portion G adapted to fit the recessed part G, the clamping-plate J adapted to fit over each of the pieces E and H between the sockets e, e and h, h, and clamping-screw K for holding the parts E, H and J together and adapted to clamp the rods which pass through the 75 sockets in place.

In testimony of which invention we hereunto set our hands,

JOHN R. HOLLOWAY.
HENRY S. JACOBS.
